(57) **CLAIM**

The ornamental design for an electronic device with attachment apparatus, as shown in the accompanying drawings and described above.

DESCRIPTION

FIG. 1 is a front, bottom, right perspective view of an electronic device with attachment apparatus in accordance with a first embodiment of the present invention;
FIG. 2 is a rear, bottom, left perspective view of the device of FIG. 1;

FIG. 3 is a bottom plan view of the device of FIG. 1;
FIG. 4 is a top plan view of the device of FIG. 1;
FIG. 5 is a right elevation view of the device of FIG. 1;
FIG. 6 is a left elevation view of the device of FIG. 1;
FIG. 7 is a front elevation view of the device of FIG. 1;
FIG. 8 is a rear elevation view of the device of FIG. 1;
FIG. 9 is a front, bottom, right perspective view of an electronic device with attachment apparatus in accordance with a second embodiment of the present invention;
FIG. 10 is a rear, bottom, left perspective view of the device of FIG. 9;

FIG. 11 is a bottom plan view of the device of FIG. 9;
FIG. 12 is a top plan view of the device of FIG. 9;
FIG. 13 is a right elevation view of the device of FIG. 9;
FIG. 14 is a left elevation view of the device of FIG. 9;
FIG. 15 is a front elevation view of the device of FIG. 9; and,
FIG. 16 is a rear elevation view of the device of FIG. 9.
The broken lines shown herein are for illustrative purposes and form no part of the claimed design.
